(57) **CLAIM**

The ornamental design for a display screen with graphical user interface, as shown and described.

DESCRIPTION

FIG. 1 is a front view of a display screen with graphical user interface showing my new design.

FIG. 2 is a front view of a second embodiment thereof.

FIG. 3 is a front view of a third embodiment thereof.

FIG. 4 is a front view of a fourth embodiment thereof.

FIG. 5 is a front view of a fifth embodiment thereof.

FIG. 6 is a front view of a sixth embodiment thereof.

FIG. 7 is a front view of a seventh embodiment thereof.

FIG. 8 is a front view of an eighth embodiment thereof.

FIG. 9 is a front view of a ninth embodiment thereof.

FIG. 10 is a front view of a tenth embodiment thereof.

FIG. 11 is a front view of an eleventh embodiment thereof; and,

FIG. 12 is a front view of a twelfth embodiment thereof.

The broken line showing of the display screen is included for the purpose of illustrating environmental structure and forms no part of the claimed design.

1 Claim, 12 Drawing Sheets
